(57) **CLAIM**

We claim the ornamental design for a burner grate, as shown and described.

DESCRIPTION

FIG. 1 is a front perspective view of a burner grate showing our new design with the lower boundary shown in broken lines forming no part of the claimed design;

FIG. 2 is a top plan view of a burner grate;

FIG. 3 is a bottom plan view thereof;

FIG. 4 is a front elevational view thereof, with the lower boundary shown in broken lines forming no part of the claimed design and the first and second side elevational views being identical images of FIG. 1; and,

FIG. 5 is a rear elevational view thereof.

The broken are included for the purpose of illustrating portions of the burner grate that forms no part of the claimed design.
